UNITED STATES PATENT OFFICE.

JULIAN E. CORBIN, OF ALAMEDA, CALIFORNIA.

VACUUM SUPPORTING DEVICE.

979,436.

Specification of Letters Patent. Patented Dec. 27, 1910.

Application filed April 5, 1910. Serial No. 553,676.

To all whom it may concern:

Be it known that I, JULIAN E. CORBIN, a citizen of the United States, residing at Alameda, in the county of Alameda and State of California, have invented certain new and useful Improvements in Vacuum Supporting Devices, of which the following is a specification.

This invention relates to vacuum supporters, and the principal object of the same is to provide novel means for pressing the edge of the vacuum cup against the surface to which the cup is attached to prevent said edge becoming released from said surface.

The invention contemplates providing the usual cup with auxiliary means which automatically and constantly exert a pressure against the sealing edge to hold the same in contact with a surface, said means being also adapted for suspending or supporting articles.

In carrying out the objects of the invention generally stated above it will be understood, of course, that the essential features thereof are necessarily susceptible of changes in details and structural arrangements, one preferred and practical embodiment of which is shown in the accompanying drawings, wherein:—

Figure 1 is a top plan view of the improved vacuum supporter. Fig. 2 is a sectional view taken on the line A—A, Fig. 1. Fig. 3 is a view in elevation of the supporter.

Referring to said accompanying drawings by numerals, 1 designates a flat surface to which the cup 2 is attached. Said cup is preferably of rubber and provided with a head 3 and the flat sealing edge 4. A supporting arm 5 is embedded in head 3 and its ends project beyond opposite portions of said head. Said arm is preferably of spring metal and is preferably provided with a

hook 6 from which articles may be suspended, the other end of said arm terminating in a spiral spring 7. From spring 7, the length of material from which said arm and springs are formed is bent to form a circular loop 8 which is of substantially the same diameter as the sealing edge 4 of cup 2, said loop being seated upon edge 4 and held there by the tension of spring 7.

In use, the cup is attached to surface 1 in the usual manner, and when attached, it will be seen that spring 7 causes arm 5 to exert a lifting pressure on head 3 and loop 8 to exert a pressure on sealing edge 4 tending to flatten the same against the surface to which the cup is attached.

What I claim as my invention is:—

1. In a device of the character described, the combination with a vacuum cup, of resilient means carried thereby and exerting a pressure on the edge thereof to hold said cup in contact with a supporting surface.

2. In a device of the character described the combination with a vacuum cup provided with a head and with a sealing edge, of a supporting arm carried by said head, a loop seated on said edge, and a spring connecting said arm and loop and exerting a pressure tending to force said arm and loop in opposite directions.

3. As a new article of manufacture, a vacuum cup provided with a head and a sealing edge, a supporting arm carried by said head, a loop seated on said edge, and a spring connecting said arm and loop, said arm, spring and loop formed of a single length of resilient metal.

In testimony whereof I affix my signature in presence of two witnesses.

JULIAN E. CORBIN.
